UNITED STATES PATENT OFFICE.

HARRY VERCOE HAIGHT, OF SHERBROOKE, QUEBEC, CANADA, ASSIGNOR TO INGERSOLL-RAND COMPANY, OF NEW YORK, N. Y., A CORPORATION OF NEW JERSEY.

VALVE MECHANISM FOR CHANNELING-MACHINES.

No. 921,240.

Specification of Letters Patent.

Patented May 11, 1909.

Application filed November 22, 1906. Serial No. 344,552.

To all whom it may concern:

Be it known that I, HARRY VERCOE HAIGHT, a subject of the King of Great Britain, and resident of Sherbrooke, in the Province of Quebec, Canada, have invented a new and useful Improvement in Valve Mechanism for Channeling-Machines, of which the following is a specification.

The object of my invention is to provide certain improvements in the construction, form and arrangement of the several parts of a valve mechanism of that type in which a main valve and an auxiliary fluid controlling valve are employed for controlling the reciprocating movements of the work piston.

My invention consists generally in an auxiliary controlling valve operated positively by the work piston in its reciprocating movements and specifically in a tappet arranged to be engaged by the end of the tool piston for moving the auxiliary controlling valve in one direction while the spring is utilized for moving the auxiliary valve in the other direction, the construction being such that a very long stroke may be imparted to a short piston.

A practical embodiment of my invention is represented in the accompanying drawing, in which—

Figure 1 represents a channeling machine cylinder and its adjacent parts in longitudinal central section, the piston being near the limit of its rearward movement, Fig. 2 is a plan view of the valve casing, Fig. 3 is a transverse section through the valve casing proper with the end caps and valves removed, the said section being taken in the plane of the line A—A of Fig. 1, Fig. 4 is a transverse section through the valve casing taken in the plane of the line B of Fig. 1, Fig. 5 is a transverse section taken in the plane of the line C—C of Fig. 1, and Fig. 6 is a detail transverse section showing a fluid pressure spring instead of a metal spring for moving the auxiliary valve inwardly.

The channeling machine cylinder is denoted by 1 and its piston by 2.

The piston chamber space to the front of the piston is denoted by 3 and the space to the rear of the piston by 4.

The rear head is denoted by 5 and the front head by 6.

The usual cushioning device 7, 8, and cushioning valve 9, are provided at the front of the cylinder chamber and the rotation de-

vice 10 is located at the rear end of the cylinder and is provided with the usual rifle bar 11 arranged to engage the work piston 2.

The valve casing is denoted by 12 within which casing there is fitted to reciprocate parallel with the tool piston 2 a main cylindrical valve 13. This valve 13 is provided with a reduced end 14 and an enlarged end 15. A chamber 16 of smaller area is provided between the reduced end 14 of the main valve 13 and its front cap 17, a bushing 18 being employed for filling the bore up to the diameter of the valve. A large chamber 19 is provided between the enlarged end 15 of the main valve and the inner end of the rear cap 20.

The main fluid supply passage is denoted by 21, from which passage branch fluid supply passages 22, 23, lead to the fluid supply port 24 which surrounds the main valve 13. 75

The main exhaust passage is denoted by 25 and it is provided with end ports 26, 27, surrounding the valve 13.

The front and rear cylinder passages are denoted by 28, 29, and the valve ports by 30, 80 31, which ports surround the valve 13, the port 30 being located between the fluid inlet port 24 and the exhaust port 26 and the port 31 being located between the fluid inlet port 24 and the exhaust port 27. The passage 28 85 opens into the cylinder adjacent to its front end and the passage 29 opens into the cylinder chamber at a distance from its rear end.

The valve 13 is reduced to form bridge ports 32, 33, arranged to alternately bring 90 the fluid inlet port 24 into communication with one of the cylinder passage ports 30, 31, and the other cylinder passage port in communication with either the exhaust port 26 or 27. When the valve 13 is at the limit 95 of its forward movement, the fluid inlet port 24 is opened to the rear cylinder passage port and the front cylinder passage port 31 is open to the exhaust 25 through the port 27. The chamber 16 at the front of the reduced end 100 14 of the valve is at all times in open communication with the motive fluid supply in the present instance, by means of a passage 34 which leads from the fluid inlet port 24.

A rocking tappet 35 of plate form is hinged 105 at 36 within a slot 37 which opens to the interior and exterior of the cylinder, the outer face of the said slot being closed by the valve casing 12. This tappet 35 is provided with a depending lug 38 upon one side of the pivot 110

36 in position to be engaged by the rear end of the work piston 2 and raised out of the interior of the cylinder 1. The valve casing 12 serves as a stop for limiting the inward rock-
5 ing movement of the tappet 35. The rear end of the tappet 35 engages the inner end of the auxiliary fluid controlling valve 39. This valve 39 is fitted to slide longitudinally through the rear cap 20 of the valve casing, 10 holes 40 and 41 being formed through the walls of the casing in alignment with the bore through the said cap 20.

The tappet and auxiliary valve are yield-
15 ingly held at the limits of their inward move-
ments by spring pressure, either by the metal
spring 42 interposed between the outer end
of the auxiliary valve and a plug 43 screwed
into the hole 40; or by a motive fluid spring
produced by forming the outer end of the
20 auxiliary valve of greater area than the inner
end, as shown in Fig. 6, and providing a mo-
tive fluid passage 51 leading from the fluid
supply passage 22 to the space 40. A port
44 leads from the chamber 19 at the enlarged
25 end of the main valve 13 to the face of the
auxiliary valve 39. A fluid inlet port 45 sur-
rounds the auxiliary valve 39 and communi-
cates at all times with the branch fluid inlet
passage 22 through a passage 46. A fluid
30 exhaust port 47 surrounds the auxiliary valve
39 and a passage 48 leads therefrom to the
exhaust port 26 of the main exhaust passage
25. This auxiliary valve 39 is provided with
35 two reduced portions 49, 50, which form
bridge ports arranged to alternately open
communication from the motive fluid supply
port 45 to the port 44 and the port 44 to the
exhaust port 47 according to the position of
40 the auxiliary valve. When the auxiliary
valve is at the limit of its outward move-
ment as shown in the accompanying draw-
ings, the chamber 19 is in open communica-
tion with the motive fluid supply 45 and the
45 exhaust port 47 is closed. When the metal
spring 42 is used the outer and inner ends of
the auxiliary valve may be of substantially
equal area and the fluid pressure on both
ends is equalized by the passage 51 before re-
ferred to, leading to the outer end of the
50 valve, and the slot 37 opening the interior of
the cylinder to the inner end of the said
valve.

A recess 52 may be provided in the cap 20
55 at the rear end of the chamber 19 which re-
cess is of the same area as the valve 13 for
providing an effective area to start the main
valve 13 toward the limit of its forward
movement when it is at the limit of its rear-
ward movement. A disk 53 of enlarged area
60 is provided at the rear end of the main valve
13 for the purpose of acting as a stop for the
valve against the inner end of the cap 20
around the recess 52.

In operation, supposing the piston to be
65 in the position shown in the accompanying

drawings on its movement toward the rear
end of the cylinder, it has raised the tappet
35 because of the engagement of its rear end
with the lug 38 and has lifted the auxiliary
70 valve into position to permit the motive fluid
to enter the chamber 19 at the rear end of
the main valve 13 thus throwing the main
valve to the limit of its forward movement
owing to the difference in area between the
75 chamber 19 at the rear end of the main
valve and chamber 16 at the reduced front
end of the said valve. This movement of
the main valve has opened the motive fluid
inlet port 24 to the port 30 of the rear cylin-
80 der passage 29. At the same time, the main
valve 13 has opened the space 3 at the front
of the work piston 2 to exhaust through the
front passage 28, its port 31, the exhaust
port 27 and exhaust passage 25. As the pis-
85 ton 2 travels toward the limit of its rearward
movement, it has closed the passage 29 to
the space 4 and has compressed the air in the
space 4 thus preventing the piston from
striking the rear head. This compression of
90 the air will start the piston on its forward
movement and as soon as it passes the mouth
of the passage 29, the motive fluid will flow
into the space 4 and complete the forward
stroke of the piston. As the end of the pis-
95 ton 2 leaves the tappet 35 the spring pres-
sure on the auxiliary valve will force the
auxiliary valve and the tappet 35 inwardly
until the forward extension of the tappet
abuts against the valve casing. This inward
100 movement of the auxiliary valve will open
the chamber 19 at the enlarged end of the
main valve 13 to exhaust through the port
47, passage 48, exhaust port 26 and exhaust
passage 25 and will also close the motive
105 fluid supply port 45 to the port 44. The
pressure exerted upon the reduced end 14
of the main valve by the motive fluid in the
chamber 16, will throw the main valve back
to the limit of its rearward movement and
thus open the motive fluid inlet port 24 to
110 the port 31 of the front cylinder passage 28
and also open the port 30 of the rear cylinder
passage 29 to the exhaust port 26 of the ex-
haust passage 25. This will cause the return
movement of the tool piston after it has
115 struck the cushioning ring 7.

By utilizing the rear end of the work pis-
ton for operating the tappet to move the
auxiliary valve, I am enabled to provide a
very short work piston with a long stroke
120 thus materially increasing the effectiveness
of the same. Furthermore, by opening the
chamber at the rear of the piston to the ad-
mission of motive fluid just before the rear
cylinder passage is closed, I am enabled to
125 procure an effective cushion for the piston,
which compressed fluid will give an impetus
to the forward movement of the piston.

In using the word "spring" in connection
130 with the means for moving the auxiliary

valve inwardly it is to be understood that either a metal spring or a fluid pressure spring is intended.

While I have shown and described the 5 valve mechanism in connection with a channelling machine cylinder, it is to be understood that it may be effectively utilized in connection with work cylinders and pistons of various types, without departing from 10 the spirit and scope of my invention; hence I do not wish to limit myself strictly to the structure herein set forth, but—

What I claim is:—

1. The combination with a cylinder and its 15 piston, of a spring pressed fluid controlling valve arranged in position to be moved positively in one direction by the rear end of the piston and in the other direction by spring pressure, the said piston having a forward 20 movement beyond the said valve.

2. The combination with a cylinder and its 25 piston, of a spring pressed fluid controlling valve, a valve operating tappet arranged in position to be engaged by the rear end of the piston for positively moving the valve in one direction, the valve being moved in the other direction by spring pressure the said piston having a forward movement beyond said tappet, and means for limiting the inward movement 30 of the tappet.

3. The combination with a cylinder and its 35 piston, of a spring pressed fluid controlling valve, a valve operating tappet mounted in the side of the cylinder between the valve and piston and arranged in position to be engaged by the rear end of the piston for positively moving the valve in one direction, the valve being moved in the other direction by spring pressure, the said piston having a forward 40 movement beyond said tappet, and means for limiting the inward movement of the tappet.

4. The combination with a cylinder and its 45 piston, of a main valve and a spring pressed auxiliary valve arranged in position to be moved positively in one direction by the rear end of the said piston and in the other direction by spring pressure for controlling the movements of the main auxiliary valve in 50 both directions, the said piston having a forward movement beyond said valve.

5. The combination with a cylinder and its 55 piston, of a main valve, a spring pressed auxiliary fluid controlling valve, an auxiliary valve operating tappet arranged in position to be engaged by the rear end of the piston to

move the auxiliary valve positively in one direction, the auxiliary valve being moved in the other direction by spring pressure for controlling the movements of the main valve in 60 both directions, the said piston having a forward movement beyond said tappet, and means for limiting the inward movement of the tappet.

6. The combination with a cylinder and its 65 piston, of a main valve, a spring pressed auxiliary valve fluid controlling valve, an auxiliary valve operating tappet mounted in the side of the cylinder between the auxiliary valve and piston and arranged in position to be engaged by the rear end of the piston for 70 positively moving the auxiliary valve in one direction, the auxiliary valve being moved in the other direction by spring pressure, for controlling the movements of the main valve 75 in both directions, the said piston having a forward movement beyond said tappet, and means for limiting the inward movement of the tappet.

7. The combination with a cylinder and its 80 piston, of a main valve, a single spring pressed auxiliary valve for controlling the movements of the main valve in both directions and a single auxiliary valve operating tappet arranged in position to be engaged by 85 the rear end of the piston to move the auxiliary valve positively in one direction, the auxiliary valve being moved in the other direction by spring pressure, the said piston having a forward movement beyond said tappet, and means for limiting the inward movement 90 of the tappet.

8. The combination with a cylinder and its piston, of a main valve having one end of smaller area than the other, the outer side of 95 the smaller end being open at all times to motive fluid pressure, and a spring pressed auxiliary valve arranged in position to be moved positively in one direction by the rear end of the said piston and in the other direction by spring pressure for controlling the movements of the main valve in both directions, the said piston having a forward 100 movement beyond said auxiliary valve.

In testimony, that I claim the foregoing as 105 my invention, I have signed my name in presence of two witnesses, this twentieth day of November 1906.

HARRY VEROE HAIGHT.
